MULTICOLOR FOUNTAIN PEN

Filed April 10, 1931

INVENTOR
ALFRED S. BEARDSLEY

BY HIS ATTORNEY

John J. Flynn

UNITED STATES PATENT OFFICE

ALFRED S. BEARDSLEY, OF MONTEVIDEO, URUGUAY

MULTICOLOR FOUNTAIN PEN

Application filed April 10, 1931. Serial No. 529,099.

This invention relates to fountain pens and in particular to one adapted for writing in different colors.

A particular object of my invention is to provide a pen having a double point, the points to be used singly in the posting of figures or other work requiring contrasting color of writing fluid. My pen is particularly adapted for bookkeeping in that one of the pens may be used for posting some of the figures in red and the other pen may be used for posting some of the figures in blue or black ink, the change from one to the other of the pens being readily made and at the same time, the shape and size of standard types of pens being preserved.

A further object of my invention is to provide a simplified construction which reduces the cost of manufacture and at the same time to provide a sturdy and leakproof construction which may be made up at low cost.

A still further object of my invention is to provide a multi-color fountain pen which is self-filling and one in which the parts are so arranged that mixing of the different colored inks is prevented and positive flow of each of the colors of ink is produced.

Changes and variations may be made in the construction shown and described without departing from the principles of the invention or sacrificing its chief advantages; hence such invention is not to be confined to the structures shown in the accompanying drawing:

35 Figure 1 is a view in sectional elevation of a fountain pen constructed in accordance with my invention.

Figure 2 is a side view of the pen holding member of the fountain pen construction, 40 this holder also serving as a valve member in bringing each of the pens successively into use to write a different color.

Figure 3 is a view in elevation of the sack holder employed in my pen construction.

45 Figure 4 is a section taken on the line 4—4 of Figure 3 and illustrates the construction of the sack holder.

Figure 5 is a view in sectional elevation of the body section of the pen in which the pen holder is mounted for rotation, and

Figure 6 is a view in sectional elevation of the cap employed to complete the fountain pen construction.

Referring to the drawing in detail, 5 indicates a body member provided with a central opening 6 in the opposite walls of the opening of which are provided, the circular seat 7. A screw bore 8 extends transversely through the body 5 concentrically of said seat 7 and is arranged to hold in close contact with said seat 7, the projecting portion 9 formed on a pen holder or rotor 10 that is snapped into position between the extended portions 11 of said body 5. The body 5 is provided with the longitudinal bore 12 constituting ink passages or flues which open into the seat 7 and which at said point are arranged to coincide with openings 13 and 14 provided in the extended portions 9 of the holder 10. This holder is shaped at its ends as at 16 to conform to the shaped end 17 of the body 5 and when either of the pens 18 or 19 are projecting beyond the body 5 and in position for use, the holder 14 completes at the opposite sides of the body 5 the shaped end 17 of said body.

The holder 14 is provided with the oppositely disposed bores 20 and 21 for the reception of the pens 18 and 19 respectively together with their feeders 22, this portion 80 of the pen construction being well known in the art and the feeders being usually forced into a pen end opening to be held in place and permit proper feed of the ink to the pen itself.

The bores 21 and 20 connect with the openings 13 and 14 through the medium of the passages 23 and 24 respectively so that ink coming down through either of the passages 12 of the body 5 will pass into either of the passages 23 or 24 depending upon which pen point 18 or 19 is in the outward position and ready for use. In Figure 1, pen 18 is outermost and in position for use with the result that the passage 12 aligns with the opening 14 and the ink flows through the passage 24 to the pen 18. At the opposite side of the holder, however, the passage or opening 13 is closed by reason of the fact that it does not register with the end of the opening 12 and

hence, pen 19 is not being supplied with ink and being positioned within the space 6 of the body, is not in use and is protected from damage by reason of its position within the body 5.

In order that the passages 12 of the body 5 may be supplied with ink of different colors, I have provided a sack holder 26, the ends of which are of circular formation as at 27 10 and are provided with the outwardly extending bosses 28 over which snap the restricted ends 29 of the sack 30 and 31. The holder 26 is provided with a longitudinal bore 32 constituting an ink passage terminating at one end at one side of the sack holder as at 33 and at the opposite end in the boss 28, positioned at the outer end of said sack holder 26. The holder is also provided with an ink bore 34 extending through the innermost boss 28 and opening at the opposite side of the holder from the passage 32. These passages 32 and 34 coincide with the ink passages 12 when the end of the holder 26 is seated in the recess 35 provided in the body 25 5 for that purpose. The sack holder is preferably held in connection with the body by a force fit which renders the same leakproof and if necessary other means may be employed to secure the two parts together although they can be taken apart for cleaning.

The sacks 30 and 31 are made of rubber and constitute reservoirs for different colored inks, the sack 30 for instance being arranged to hold blue ink while the sack 31 could be 20 used to hold red ink and they are encased in the barrel 36 which has threaded connection as at 37 to the upper end of the body 5, the barrel 36 being also threaded at its open end where it engages the body 5 for the purpose of receiving the threaded end 39 of a cap 40. This cap 40, as is usual in fountain pens bears the clip 41 and its internal bore is reduced as at 42 to provide a receptacle for the pen when the cap is placed over the body 5.

An important feature of my invention is the use of the bolt 43 whose end is threaded as at 44 into a suitable ferrule 45 which is countersunk in the body 5 and is flush with the surface of said body. This bolt is adjustable to draw together the opposite sides or extensions 11 of the body 5 and to securely hold in position the holder 10 to prevent leakage of ink and at the same time permit rotation of the holder 10 to place either pen 40 18 or 19 in position for use and at the same time to align either the opening 14 or the opening 13 with either of the channels 12 so that the proper ink may be fed from either the sack 30 or sack 31 to the pen to be used.

In filling the pen, it is simply necessary to remove the barrel 36 by unthreading the same from the body 5 and dipping each of the pens 18 and 19 into proper colored ink, the sacks 50 30 and 31 can be manipulated successively to

fill themselves by suction through the proper pen 18 or 19 in the usual manner.

All of the parts of my pen construction may be made of hard rubber or composition with the exception of the pens and the bolt and ferrule, the sacks 30 and 31 being of the usual pliable rubber of the compressible type employed as reservoirs in fountain pens.

It is evident, therefore, that I have provided a double duty fountain pen which may be employed to write in contrasting colors and in which the construction affords protection for the pen not in use and prevents leakage of ink therefrom. My construction also provides for sealing the ink channels not in use with the result that there is no mixture of the ink and no soiling of the fingers at the movable parts of the pen.

It is evident, too, that in a construction of the character referred to, I have provided a simplified means of filling the pen with the contrasting color inks with a minimum of delay and trouble and have provided a construction which lends itself readily to the easy cleaning of the pen and quick separation of all of the parts for a thorough cleansing.

My invention is not to be restricted to the precise details of construction shown since various changes and modifications may be made therein without departing from the scope of the invention or sacrificing the advantages derived from its use.

What I claim is:—

1. In a writing implement, a body member having a plurality of ink channels, a holder mounted in said body member and having passages therein, a pen in each passage, a multi-color ink supply for the said body channels and means for revolvably mounting the holder in the body whereby one of the passages and one of the channels coincide.

2. A pen of the character described comprising a body having passages and an opening therein, a holder revolvably positioned in said opening, pens in said holder and said holder having a channel leading from each pen to the side of the holder, and arranged to coincide with one of the body passages when the holder is in a predetermined position, and means for supplying ink to said passages.

3. A pen of the character described comprising a body having passages and an opening therein, a holder revolvably positioned in said opening, pens in said holder, said holder having a channel leading from each pen to the side of the holder and arranged to coincide with one of the body passages when the holder is in a predetermined position, and means for supplying ink to said passages comprising a sack holder secured to said body, a plurality of sacks on the holder, and said sack holder having a passage from each sack connecting with each passage of said body.

4. In a pen of the character described, a body having passages therein, a rotor in the body having a pen at opposite ends thereof, said rotor having channels therein opening at the sides thereof, means for supplying an ink of different color to each of said passages, and each of said rotor channels being arranged to coincide with its respective body passage when the rotor is revolved to position the pen for use.
5. In a pen of the character described, a body having passages and an opening therein, a holder revolvably positioned in said opening and having channels therein, pens in said holder, the said channels leading from each pen to the sides of the holder and arranged to coincide with the body passages when the holder is in a predetermined position, means for supplying ink to said passages comprising a sack holder arranged to be secured to said body, a plurality of sacks on the holder, said sack holder having a passage leading from each sack, and connecting with each passage of said body, and a barrel constituting a housing for the sack holder.

In testimony whereof I affix my signature.

ALFRED S. BEARDSLEY. [L.S.]
